[57] **CLAIM**

The ornamental design for a combined bathtub and shower enclosed, as shown and described.

DESCRIPTION

FIG. 1 is a right, top, front perspective view of a combined bathtub and shower enclosure embodying my new design; FIG. 2 is a front elevational view thereof; FIG. 3 is a rear elevational view thereof; FIG. 4 is a top plan view thereof; FIG. 5 is a bottom plan view thereof; FIG. 6 is a right side elevational view thereof; FIG. 7 is a left side elevational view thereof; FIG. 8 is a cross-sectional view taken along line 8—8 of FIG. 6; FIG. 9 is a cross-sectional view taken along line 9—9 of FIG. 2; FIG. 10 is a cross-sectional view taken along line 10—10 of FIG. 4; FIG. 11 is a cross-sectional view taken along line 11—11 of FIG. 4; and, FIG. 12 is a cross-sectional view of a second embodiment which is a mirror image of that shown in FIG. 9, the front elevational view being identical to that shown in FIG. 2, the rear elevational view being a mirror image of that shown in FIG. 3, the top plan view being identical to that shown in FIG. 4, the bottom plan view being a mirror image of that shown in FIG. 5, the left side elevational view being a mirror image of that shown in FIG. 6, and the right side elevational view being a mirror image of that shown in FIG. 7. The broken line representation of a hole in FIGS. 7 and 10 is for the purpose of illustration only, and forms no part of the claimed design.
